UNITED STATES PATENT OFFICE.

EVERETT N. MURPHY AND MERRITT N. MURPHY, OF CHICAGO, ILLINOIS, EXECUTORS
OF JOHN D. MURPHY, DECEASED.

MACHINE FOR BULGING TANK-HEADS.

1,013,046.

Specification of Letters Patent. Patented Dec. 26, 1911.

Application filed January 22, 1908. Serial No. 412,143.

To all whom it may concern:

Be it known that JOHN D. MURPHY, deceased, late a citizen of the United States, residing at Chicago, in the county of Cook 5 and State of Illinois, did invent new and useful Improvements in Machines for Bulging Tank-Heads, of which the following is a specification.

The invention relates to machines for bulging tank-heads.

In this art it has heretofore been common practice to bulge flanged heads by hammering and also to shape them in machines comprising male and female formers 15 or dies. An objection to the hammering method is, that the metal is not evenly distributed throughout the head so that portions thereof may be weaker than others, and the head will be irregular in shape and 20 will not endure the pressure or strains that a head, in which the metal is evenly and uniformly distributed, will. An objection to the method in which male and female dies are employed, is that the dies are costly. 25 Furthermore, they become worn so they must be reshaped. The matter of cost is a material one, particularly when heads of many different sizes or shapes are employed.

The invention designs to overcome these 30 objections to the aforesaid methods, by providing a machine which is simple in construction, can be produced at a low cost and which will distribute the metal of the blank evenly in the bulging operation.

The invention consists primarily in providing a machine for bulging a blank which has been heated to render the metal thereof ductile, by fluid under pressure, such as air, to force the metal of the face of the blank 35 into concavo-convex shape, while the metal is still ductile, thus avoiding entirely the employment of a powerful and expensive die-operating press and the male die as heretofore.

The invention further consists in the several novel features hereinafter set forth and more particularly defined by claims at the conclusion hereof.

In the drawings: Figure 1 is a central vertical section of a bulging machine embodying the invention. Fig. 2 is a plan, a portion of the wall of the upper member being broken away. Fig. 3 is a detail section on an enlarged scale illustrating the position 55 of the blank after it has been bulged.

The improved machine comprises a lower member 10 which is mounted on legs 11. Said member comprises an annulus 12 having a vertically extending flange or rim 13, and a bottom plate 14 secured to the annulus by rivets 15, the bottom 14 being preferably formed of heavy plate metal, for the sake of lightness and strength. This lower member 10 serves as a die for determining the shape of the blank and is adapted to 60 receive a blank 16 provided with a side-flange 17. This blank consists of a plate which has been previously shaped to provide the cylindrical side-flange 17 whereby the head is usually secured in a cylinder or 65 tank. Before placing the blank in the die-member 10 it is heated to render the metal ductile under pressure. The bottom of die-member 10 is of concave form, corresponding to the bulge to be placed on the 70 head of the blank. Resultantly, when fluid under pressure is applied to the upper face of the heated blank the head-portion 16 of the blank will be forced downwardly and given a shape corresponding to the bottom 75 of the die-member 10. Holes 18 are formed in the bottom-plate 14 to permit the air to escape as the blank is being bulged, and also to permit scale or dirt or chips to fall 80 through the bottom.

The machine comprises an upper-member 20 having a fluid-chamber 22 therein, and adapted to be connected to the lower or die-member by pivoted clamp-screws 21 and whereby a blank placed between the members will be clamped therebetween to secure the same in die-member, and furthermore the upper member will be pressed into engagement with the blank so that air under pressure will be confined above the heated blank in chamber 22 of the upper member. Member 20 comprises an annulus 23, a top 90 24 preferably formed of plate metal and secured by rivets 25 to the annulus 23, and a rim or flange 26 adapted to pass within the side-flange of the blank, and to said rim is secured, by bolts 28, a liner or gasket 27. This liner or gasket is made of insulating material, such as asbestos, which is slightly yielding so that the upper member will be 95 secured into engagement with the blank while the metal is ductile and thus a suitable air-tight joint will be provided between the blank and the chamber-member 20. This insulating liner is furthermore 100 105 110

disposed to engage the blank adjacent the flange 17 so that as the blank is bent, the air-tight joint will remain.

Clamp-screws 21 are pivoted as at 30 in one of the members and are adapted to pass into slots 31 of the other member so they can be quickly and conveniently manipulated to secure the members together to clamp a blank between the members and so 10 they can be readily manipulated to disconnect the members after a bulging operation.

A pipe 32 is connected to the top-member to supply air under pressure to chamber 22, being connected by a flexible tube 33 so said 15 member may be placed into and out of operative position, to a suitable source of air-supply, such as a reservoir or tank, containing compressed air under the necessary pressure. A valve 34 is provided for controlling 20 the supply of fluid to the chamber above the blank. A pressure-gage 35 is provided so the pressure of the fluid in chamber 22 may be determined. A safety-valve 36 of usual and suitable construction is also connected 25 to the upper member 20 to prevent excessive pressure from being supplied to the chamber.

The operation of the machine will be as follows: A flanged blank provided with side-flange 17 which has been previously heated to render it ductile, is placed into the concave or female die-member 10 when the upper member 20 is removed. Next, the upper member is clamped into position illustrated 35 in the drawings. The heated blank will then be securely clamped between the upper and lower members of the machine and insulating-liner 27 will engage the blank adjacent the flange 17 of the blank, forming an 40 air-tight joint between the chamber-member 20 and the top of the blank, and will also clamp the blank in the lower member or female die so that the air-tight joint will be retained. With the blank thus clamped in 45 the machine, valve 34 will be manipulated to cause air under sufficient pressure to enter chamber 22, whereupon the ductile metal of the head-portion 16 of the blank will be gradually bulged and forced downwardly 50 into shape determined by the concave bottom of die-member 10. During this bulging operation, the liner 27 will cause the air-tight joint between the blank and the pneumatic member 20 to be retained. When the 55 blank has been bulged as illustrated in Fig. 3, the supply of air will be cut off and the air in the chamber 22 will be exhausted therefrom, either by means of a port in valve 34 or by loosening bolts 21 to open the joint between the bulged blank and the liner 27 on member 20. The latter member can then be lifted out of the bulged head and the latter removed so the operation may be repeated.

60 The invention provides a simple, inex-

pensive machine for pneumatically bulging tank-heads and which results in even distribution of the metal during the bulging operation.

The invention is not to be understood as 70 restricted to the details set forth since these may be modified within the scope of the appended claims without departing from the spirit and scope of the invention.

Having thus described the invention, 75 what we claim as new and desire to secure by Letters Patent, is:

1. A machine for shaping metallic tank-heads comprising the combination of a die-member adapted to receive and hold a 80 heated flanged blank and for determining the bulge of the head, a member provided with a pneumatic fluid-chamber for causing fluid under pressure to force the heated blank against the die while the metal of the 85 blank is ductile, and means for engaging the heated blank adjacent the flange thereof to provide a suitable connection between the chambered member and the blank.

2. A machine for shaping metallic tank-heads, comprising the combination of a die-member adapted to receive and hold a heated blank having a side-flange thereon and for determining the bulge of the head, a member provided with a pneumatic fluid-chamber for causing fluid under pressure to force the heated blank against the die-member while the metal of the blank is ductile, and means on said members respectively for engaging the heated blank adjacent the flange thereof and on opposite sides thereof respectively.

3. A machine for shaping metallic tank-heads comprising the combination of a die-member having a concave wall and a flange 10 around said wall and adapted to receive a flanged heated blank, a member provided with a pneumatic fluid-chamber for causing fluid under pressure therein to force the heated blank against the concave wall 11 while the metal of the blank is ductile, and means on said chamber-member adapted to pass into the blank and to engage it adjacent the flange of the blank.

4. A machine for shaping metallic tank-heads comprising the combination of a die-member provided with a concave wall and a flange around said wall and adapted to receive a flanged heated blank, a member provided with a pneumatic fluid-chamber 1 for causing fluid under pressure therein to force the heated blank against the concave wall while the metal of the blank is ductile, and means for holding the members together so the blank will be clamped therebetween.

5. A machine for shaping metallic tank-heads comprising the combination of a die-member provided with a concave wall and a flange around said wall for receiving a 1

- heated blank having a side-flange, a member provided with a pneumatic fluid-chamber for causing fluid under pressure therein to force the metal of the heated blank 5 against the concave wall while the metal of the blank is ductile, insulating - means for engaging the blank adjacent its flange, and means for clamping the blank between the members.
- 10 6. A machine for shaping metallic tank-heads comprising the combination of a base-member having a concave bottom for determining the bulge of the head, a movable member provided with a pneumatic 15 fluid-chamber for causing fluid under pressure therein to force the metal of the heated blank against the concave bottom while the metal of the blank is ductile, means for supplying fluid under pressure to said 20 fluid-chamber, and means on said movable member for engaging a flanged blank adjacent its flange, and means for clamping the members together.
7. A machine for shaping metallic tank-heads comprising the combination of a die-member provided with a concave wall and a flange around said wall and for determining the bulge of the head, a member provided with a pneumatic fluid-chamber
- for causing fluid under pressure therein to 30 force a heated blank against the concave wall while the metal of the blank is ductile, said chamber-member being provided with a flange or rim for engaging a flanged blank adjacent its flange, means for supplying fluid under pressure to said chamber, and means for holding the members together.
8. A machine for shaping metallic tank-heads comprising the combination of a die-member provided with a concave wall and a flange around said wall and for determining the bulge of the head, a member provided with a pneumatic fluid-chamber for causing fluid under pressure therein to 35 force the heated blank against the concave wall while the metal of the blank is ductile, an insulating ring on said chamber-member for engaging a heated blank, and means for holding the members together so a blank 40 will be clamped therebetween.
